UNITED STATES PATENT OFFICE.

C. RAYMOND HEIZMANN, OF READING, PENNSYLVANIA, ASSIGNOR TO THE PENN HARDWARE COMPANY, OF SAME PLACE.

APPLE PARER, CORER, AND SLICER.

SPECIFICATION forming part of Letters Patent No. 256,214, dated April 11, 1882.

Application filed January 4, 1882. (Model.)

To all whom it may concern:

Be it known that I, C. RAYMOND HEIZMANN, of Reading, Pennsylvania, have invented a new and useful Improvement in Machines for Paring, Coring, and Slicing Apples, of which improvement the following is a specification.

The machine herein described belongs to the class of apple-parers in which the apple bearing shaft is susceptible of certain free longitudinal movements through its bearings toward and from the paring-knife without rotation, as well as the advancing and receding movements regulated by its screw-thread.

My object is to make a substantial machine, which shall be at once simple in form, positive in action, and inexpensive in construction.

I will now proceed to state the nature of my invention, referring to the annexed drawings, in which—

Figure 1 is a side elevation, and Fig. 2 a plan, of the same; Fig. 3, a sectional elevation on the line $x-x$ of Fig. 1; Fig. 4, a sectional elevation on the line $y-y$ of Fig. 1. The other views represent details, Fig. 5 being a longitudinal section of the part a of the frame, showing the lever or latch u , slide t , and spring t^1 in elevation; Fig. 6, a front elevation of the core-exeller a^3 , and Fig. 7 a cross-section of the same on the line $x-x$ of Fig. 6; Fig. 8, a side elevation of the track-bar k ; Fig. 9, a section of the same on the line $x-x$ of Fig. 8, and Fig. 10 a section of the same on the line $y-y$ of Fig. 8; Fig. 11, a plan of the slide t , and Fig. 12 a cross-section of the same on the line $x-x$ of Fig. 11; Fig. 13, a front elevation of the engaging-bolt o , and Fig. 14 a cross-section of the same on the line $x-x$ of Fig. 13.

$a a' a^2$ is the frame, the top part, a^2 , of which is hollow or chambered, as shown in Fig. 4. b is the paring-knife, which is adjustably secured, as by a screw, to the ordinary upright trough-shaped standard, c , which has a rotary vibration on a vertical shaft, (not shown,) by which it is attached to the cross arm or stop d' of the horizontal shaft d , the latter being surrounded and actuated by the spiral spring e , all constructed in a well-known form and manner, except that the bearings of the shaft d , instead of being a part of the frame, as is usual, are attached to the slide t , hereinafter described.

f is the apple-bearing shaft, which is screw-threaded, as shown, and has the crank g at its rear end, and the fork, consisting of the beveled head h and tines i in one piece, screwed or riveted to the front end of said shaft f . The shaft f passes through the smooth-bored upright projections j and j^2 of the frame.

k , Figs. 1 and 8, is a bar which extends through the chamber in the upper part, a^2 , of the frame. The forward end of this bar is curved upward in a plane at right angles to its length, the curved portion being recessed or notched, as shown at k' in Figs. 8 and 9. The bar k has also a downward projection, k^2 , the foot of which enters the slot in the paring-knife slide t . A track, l , is formed in relief on each face of the bar k by cutting away a part of the thickness of the bar, forming notches or depressions m and n at either end of said tracks. The tracks l are beveled at their front ends, as shown in Figs. 1 and 8. The rear end of the track-bar k comes in contact with the crank g .

o , Figs. 1, 2, 13, and 14, is a bolt cored out from top to bottom, as shown in Fig. 13. It is loosely held in an upright position against the flat face of the upright part a' of the frame by means of an ordinary undercut stud, p , which projects from the face of the frame and permits said bolt o to slide freely up and down thereon. The lug q projects from the top of the bolt o , as shown in Figs. 1, 2, and 13. The bolt o is provided with projections s and s' , which are short segments of screw-threads, that in the operation of the machine are caused to engage the thread of the shaft f .

t , Figs. 1, 2, 5, 11, and 12, is a slide resting on the horizontal part a of the frame. It carries a side appendage, t' , which supports the upright bearings t^2 of the paring-knife. It is provided with the lug t^3 , to which one end of the spring t^1 is hooked or attached. It has at its rear end the lug t^5 , which is brought into contact with the under side of the foot-lug o' of the engaging-bolt o , and thus keeps the bolt o from dropping down into the notches n . It also has the catch t^6 , Figs. 1, 5.

u , Figs. 1, 2, 3, and 5, is a lever or latch pivoted to the frame at u^2 . It has a shoulder, u^3 , near its rear end, which is intended to en-

gage the catch t^6 of the slide t . The rear end, u^4 , of the latch u is made heavier than its front end.

a^3 , Figs. 1, 2, 6, and 7, is the core-expeller. 5 Its rim or flange a^4 fits loosely in recesses or notches in the curved head k' of the track-bar k , and it is thus kept on the fork-tines, which extend through apertures (shown in Fig. 6) in the expeller. The core-expeller has a longitudinal movement on the fork, controlled by 10 the movement of the track-bar k .

b^2 is an ordinary coring and slicing knife.

When the bolt o is down—that is to say, when it is in this position—it holds, while the 15 screw-thread segments s and s' are disengaged from the thread of shaft f , the lug q in contact with shaft f , which can then be moved freely back and forth through its bearings in the projections j and j' without rotation. At the completion 20 of the operation of paring an apple the shaft f is drawn back by the operator, the core being held within the fork-tines with sufficient firmness to cause the core-expeller and the track-bar to go back with the shaft until the 25 two shoulders n^2 (one on each side of the track-bar k) abut against the projections s^2 and s^3 , and thus arrest the further withdrawal of the track-bar k , while the fork-shaft is still free to be further drawn back until the beveled head 30 h of the fork comes in contact with the lug q of bolt o , in which further movement of the shaft f it draws the fork-tines through the core-expeller and throws out the core. Then with a little extra force the fork-head h is drawn under lug q , raising bolt o , and lifting the 35 projections s^2 and s^3 above the shoulders n^2 about level with the beveled ends of the tracks l , freeing the track-bar k . The bolt o is now up—that is, as shown in Fig. 1—being held up by 40 the fork-head, and if an apple be then stuck on the fork, this act presses back the core-expeller on the fork-tines, and also presses back the track-bar k , the foot of the downward projection k^2 of which pulls back the slide t against the action 45 of the spring t^4 until the catch t^6 passes under and behind the shoulder u^3 of the pivoted lever u , the heavier rear end, u^4 , of which drops, causing the shoulder u^3 to engage the catch t^6 , and thus hold the slide t . While the 50 slide t is held as last described the end t^5 of the slide is underneath the foot-lug o' of the engaging-bolt o , and is ready to hold up said bolt o , which would otherwise drop into the notches n upon the removal of the fork-head 55 from under the lug q . The projections s^2 and s^3 of bolt o are now in position to mount the tracks l , and thus bring the screw-segments s and s' into position for engaging the screw-thread of shaft f when this shaft is pushed 60 forward. The shaft f , bearing the apple, can be pushed forward toward the paring-knife

without rotation until the thread of this shaft engages the segments s and s' , from which period until the end of its forward movement the shaft f is advanced by turning the crank g . 65

It will be seen that the track-bar k is pressed forward by the crank, and that when the fork-head h has passed the paring-knife b the shoulder k^3 of the projection k^2 slides up the incline u^6 of the pivoted lever u , pressing down the 70 lighter end of this lever and disengaging the shoulder u^3 from the catch t^6 of slide t , which by the action of the spring t^4 is then moved forward, carrying the paring-knife with it and causing this knife to press with a following 75 pressure against the rear part of the advancing apple, and thus more effectually pare that part of the apple. The forward movement of the slide t takes this slide from under the foot-lug o' of bolt o , and the shaft f being revolved, 80 the track-bar is pushed forward until the projections s^2 and s^3 reach the notches m , allowing the bolt o to drop and break the engagement between the segments s and s' and the shaft-thread. The withdrawal of the shaft f 85 and the other above-described operations can then be repeated, and so on indefinitely.

Instead of employing two tracks l , one on each face of bar k , as above described, and the two corresponding projections, s^2 and s^3 , and 90 the two screw-segments s and s' , but one of such tracks l may be used, and in such case only the corresponding one of the two projections s^2 and s^3 and of segments s and s' are required. I prefer, however, the form of construction first described, because it secures 95 more freedom of action in the engaging-bolt o .

I claim—

1. In an apple-parer, the combination of the fork-shaft f , the crank g , the track-bar k , provided with a track, l , the paring-knife slide t , and engaging-bolt o for the purpose of effecting engagement between the said bolt o and shaft f , substantially as set forth. 100

2. The combination of the fork-shaft f , the track-bar k , with its downward projection k^2 , the spring-actuated paring-knife slide t , the said knife being mounted thereon, and the pivoted latch u for giving to the paring-knife a following pressure on the apple, and thus more 110 completely paring the rear part of the apple, substantially as set forth.

3. The combination of the fork-shaft f , the fork with its beveled head h , the track-bar k , provided with a track, l , the bolt o , and the sliding core-expeller a^3 for the purpose of clearing the apple-core from the fork, substantially 115 as set forth.

C. RAYMOND HEIZMANN.
